UNITED STATES PATENT OFFICE.

MARY CUNNINGHAM, OF BELLEVUE, IDAHO.

DESIGN FOR A TOY.

SPECIFICATION forming part of Design No. 22,626, dated July 18, 1893.

Application filed June 15, 1893. Serial No. 477,752. Term of patent 7 years.

To all whom it may concern:

Be it known that I, MARY CUNNINGHAM, a citizen of the United States, residing at Bellevue, in the county of Logan and State of Idaho, 5 have invented a new and original Design for Toys, of which the following is a specification.

The invention relates to a new and original design for toys.

The object of the present invention is to 10 provide an ornamental and attractive toy; and the essential feature resides in a toy having a representation of an apple at one end of a strip of rubber, and a ring and whistle at the other end of the rubber.

15 The figure of the drawing is a perspective view of a toy showing my new and original design.

Referring to the drawing, 1 designates a strip of rubber having a finger ring 2 at one

end with a whistle 3. At the other end of the 20 rubber is an apple-shaped ball 4 having two sections 5 and 6; the section 5 bears a representation of the face of a watch; and the section 6 has a representation of Columbus. The sections 5 and 6 when closed form an apple-shaped return ball. It will be seen that the toy presents an appearance which is ornamental and attractive. 25

What I claim is—

The design for a toy herein shown and described. 30

In testimony that I claim the foregoing as my own I have hereto affixed my signature in the presence of two witnesses.

MARY CUNNINGHAM.
